[57] CLAIM

The ornamental design for a toaster, as shown and described.

DESCRIPTION

FIG. 1 is a front elevational view of a toaster showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

The design is characterized by the shape of the toaster, the casing of which is characterized by a pair of opposite ellipsoidal long side walls. The top surface presents a rectangular hollow. At the right side of this toaster, there is one button in the form of a ball for lowering bread. In the front of the toaster, at right, there is one round button for the thermostat. The lower part of the casing exhibits an elongated through-aperture, which opens in a longitudinal groove in each side face of the middle casing, to allow the evacuation of crumbs.
